Primary Examiner — Lilyana Bekic*Assistant Examiner* — Aula Soroush(74) Attorney, Agent, or Firm — McAndrews, Held & Malloy, Ltd.(57) CLAIM

The ornamental design for a bra, as shown and described.

DESCRIPTION

FIG. 1 is a front view of a bra showing my new design;
FIG. 2 is a rear view thereof;

FIG. 3 is a right side view thereof;

FIG. 4 is a left side view thereof;

FIG. 5 is a front left perspective view thereof; and,

FIG. 6 is a rear perspective view thereof.

The broken lines in the drawings illustrate portions of the bra that form no part of the claimed design.

1 Claim, 6 Drawing Sheets(56)
